FIBER CONTAINER

Filed April 21, 1926

UNITED STATES PATENT OFFICE

PAUL F. BOEYE, OF ST. PAUL, MINNESOTA, ASSIGNOR TO WALDORF PAPER PRODUCTS COMPANY, A CORPORATION OF MINNESOTA

FIBER CONTAINER

Application filed April 21, 1926. Serial No. 103,530.

This invention relates to fiber containers made from paper stock or other disintegrated, fibrous material in sheet form and is particularly adapted for shipping meat, such as pork loins, or other irregularly shaped merchandise.

Many difficulties have been met with in devising a fiber container which is durable enough for practical use in the shipping of such heavy goods. One of the principal difficulties is in providing a fastening means for the closure of such containers, which will permit a certain amount of bulging or distortion of the container, and at the same time be sufficiently secure to prevent breaking the cover open in shipping or handling the boxes.

I have heretofore devised a body for such a container which meets the requirements of strength. The means by which the body is rendered peculiarly strong are described and pointed out in my pending applications for patents, bearing Serial Nos. 743,276 and 76,415, filed on October 13, 1924, and December 19, 1925, respectively.

The present invention comprises a novel and efficient arrangement of a cover or closure flap for such a container and means for preventing the breaking loose, shearing or opening of the cover during shipping, storing or handling of the boxes.

The invention will be best understood by reference to the accompanying drawings, in which Figure 1 is a perspective view of the finished container with the cover closed and secured; Fig. 2 is a plan view of the assembled blanks and reinforcing members laid flat and ready for folding in box form; Fig. 3 is a transverse section through the container showing the cover flap and fastenings therefor in open position; Fig. 4 is a typical section illustrating the method of securing the liner to the outer walls of the box and reinforcing members; Fig. 5 is an enlarged detail in section, showing the arrangement

of the outer closure flaps in relation to the wires for holding the flaps in closed position and Fig. 6 is a similar section showing an alternate arrangement of fastening for the normally free edges of the outer cover flaps. 50

As best shown in Fig. 2, my improved container has a main outer sheet of heavy fiber board 7, which is slotted and scored to form the outer side panels 8, cover panels 9, bottom 10, a cover flap 11 and end flanges 12. 55 End panels 13 are formed from separate sheets of the fiber board, which are secured to the outer surfaces of a pair of flanges 12 at the ends of the bottom 10. These end panels 13 are scored as indicated in dotted lines in Fig. 2 to form outer cover flaps 14, adapted to be folded upon the outer surface of the main cover panel 9 for fastening said cover in closed position.

Integral flanges 15 are formed by score 65 lines 16 on the extremities of the flaps 14 and are adapted to be folded upon the inner surfaces of said flaps and secured thereon by means of wire staples 17. The folded flanges 15 thus form hook-like members along the 70 normally free edges of the flaps 14, adapted to receive wire retaining members 18, which are inserted to hold the flaps 14 in closed position, as hereinafter described.

Extending across the sides 8, bottom 10 75 and main cover panel 9 near the ends of the box, is a pair of wires 19. The wires 18 and 19 are secured upon the outer surfaces of the several panels by staples 20 (see Fig. 4). The box is preferably lined by a sheet of corrugated board 21 extending over the inner surfaces of the cover 9, sides 8 and bottom 10, and secured in place by the staples 20, as shown in Fig. 4.

In erecting the box, the end panels 13 are 85 first folded to a position perpendicular to the bottom panel 10, and then the sides 8 are raised to upright position and the flanges 12 on said sides are secured to the outer surfaces of the panels 13, as shown in Fig. 1. 90

The goods to be shipped may now be placed in the box and the flap 11 turned inward at one side and the main cover panel 9 closed upon said flap, with the end flanges 12 adjacent to the inner surfaces of the end panels 13. The outer cover flaps 14 are then folded upon the cover panel 9 with the wires 19 upon the outer surfaces of said flaps.

The ends of each wire 19 may now be secured one to the other by twisting and simultaneously drawing the wire tight about the box. Finally, the free portions of the wires 18 are inserted beneath the flaps 14 and drawn snugly into the angles formed between the flanges 15 and normally free edges of the flaps 14 (see Fig. 5), and the ends of each of the wires 18 are secured together to draw the wires tightly about the box.

It will be noted that the cover flaps 14 cannot bulge away from the cover of the box, both by reason of the wires 19 engaging said flaps near their junction with the body of the box and also by reason of the wires 18, which engage the hook-like projection formed by the flanges 15. Forces tending to break out the ends of the box are transmitted directly by the flaps 14 to the metal retaining members, 18. The portion of the wires 18 encircling the body of the box are offset toward the middle thereof from their portions engaging the flanges 15, so that when the wires are drawn tight and fastened, the flaps 14 will be pulled firmly inward from the end of the container. The stitches 17 are applied to the reinforced edges of the flaps.

In the alternate form of construction shown in Fig. 6, the normally free edges of the flaps 14 have the foldable flanges 15, but said flanges are secured in the form of a loop across the edge of the flaps 14 by means of staples 23. With this form of box, the wires 18 for securing the free edges of the flaps 14 are inserted through the loop so formed. It will be obvious that, if desired, the staples 17 and 23 may be omitted entirely, leaving the flanges 15 free to receive the wire 18 on their upper surfaces.

The wires 19 further operate to clamp the ends of the cover panel inward, so that the ends of said panel are securely held in position to abut against the rigid panels 13 at each of the four vertical corners of the box. Thus, forces tending to warp or distort the cover diagonally between corners are opposed by the rigid board itself, and the covering fastenings do not receive the resulting shearing strains. This is true, even where by reason of irregular shape and divers size of the goods packed in the box, the cover is caused to bulge outward, and such bulging of the cover does not in any way interfere with secure fastening of the cover with the wires 18 and 19. It may further

be observed that in fiber containers of the class under consideration, there is a tendency of the wires to shear or cut the cover or closure member, particularly during the handling of the filled containers. This is prevented in the present invention by reason of the fact that the wires are not in contact with the cover panel 9. The flaps 14 carry the shearing force of the wires 19 and the flanges 15 that of the wires 18.

Having described my invention what I claim as new and desire to protect by Letters Patent is:

1. In a fiber container the combination with a cover adapted to close the top of the container, of a retaining flap arranged to be folded over an end of said cover, a backwardly turned flange on the end of said flap, a wire fastening member encircling the end of the container and upon the outer surface of said flap and a second wire fastening member encircling the container adjacent to the inner end of said flap and arranged to engage said flange.

2. In a container for shipping heavy goods and formed from a plurality of separate blanks, a main body blank forming the bottom, two sides and a cover panel, a separate end panel secured to said sides and the bottom, a cover flap formed on said end panel to extend upon the outer surface of said cover panel, a wire retaining member secured to the outer surfaces of said sides and arranged to be extended across the outer surface of said cover panel but being unattached thereto, said wire member being adapted to be drawn tight and secured about the container to retain said flap upon the outer surface of said cover panel and means for securing the portion of said wire extending across the cover panel along the normally free edge of said cover flap.

3. In a container adapted for shipping heavy objects and formed from a plurality of separate blanks, a main body blank forming two sides, a bottom and a cover panel, a separate end blank secured to the sides and bottom and having a cover flap extending upon the outer surface of said cover panel, a backwardly folded, reinforcing flange extending along the normally free edge of said flap and a wire-retaining member encircling the container and extending in the angle formed by said flange and flap to secure the free edge thereof in engagement with said cover.

4. In a container for shipping heavy goods and formed from a plurality of separate blanks, a main body blank forming the bottom, two sides and a cover panel, a separate end panel secured to said sides and the bottom, a cover flap formed on said end panel to extend upon the outer surface of said cover panel, a pair of wire retaining members secured to the outer surfaces of said

sides and adapted to be extended entirely around the container to retain said flap upon the outer surface of said cover panel and a flange arranged on the normally free end of said flap to engage the portion of one of said wire members extending across the cover panel, the other of said members extending freely upon the outer surface of said flap to securely retain the same in contact with said cover panel.

In testimony whereof, I have hereunto signed my name to this specification.

PAUL F. BOEYE.
